STOCKING

Herbert N. Goodman, New York, N. Y.

Application March 4, 1953, Serial No. 23,887

Term of patent 14 years

(Cl. D47—7)

To all whom it may concern:

Be it known that I, Herbert N. Goodman, a citizen of the United States of America, residing at the city, county, and State of New York, have invented a new, original, and ornamental Design for a Stocking, of which the following is a specification, reference being had to the accompanying drawing, forming part thereof.

In the drawing:

Fig. 1 is a side view perspective of a stocking showing my new design, the foot portion being shown as it would appear when worn, while the leg and top are shown in flat folded condition.

Fig. 2 is a rear view of the lower portion thereof.

I claim:

The ornamental design for a stocking, substantially as shown.
